UNITED STATES PATENT OFFICE.

CARL M. PAGE, OF CHICAGO, ILLINOIS, ASSIGNOR TO GEORGE FABYAN, OF GENEVA,
ILLINOIS.

APPARATUS FOR DISTILLING AND CRACKING CRUDE PETROLEUM AND DISTILLATE.

Application filed August 26, 1920. Serial No. 406,179.

In the manufacture of gasoline or motor spirits by the treatment of high boiling point residual, particularly the residual from the fractional distillation of paraffine base petroleum, after the lower boiling point distillates are removed, a lower boiling point product of the paraffine series is obtained by "cracking". This is accomplished by raising the boiling point of the liquid residue 10 by means of back pressure on the liquid and vapors which are maintained under such pressure throughout their course from the still through the condenser and while undergoing condensation. This process is 15 known as the "Burton process" and such distillation of petroleum under pressure has been safely carried out on a large scale.

However, in this process and in any of the many allied processes the great danger and 20 chief difficulty is due to the deposition of hard flinty coke on the inner walls of the heating element. Some who have had considerable experience in cracking oil have said that the coke is forced into combination with the iron, making it brittle and utterly unable to withstand the high temperature and pressure employed. At any rate, the greatest deposition of the carbon 25 occurs where the wall of the still is hottest, causing a local overheating at that point. Under such conditions the strength of the steel becomes an unknown quantity and as likely as not it yields to the stress without any warning. Oil vapors of a temperature 30 around 650° F. ignite spontaneously when they evolve from a still into the surrounding atmosphere and in cracking processes the temperature is 750° to 850° F., and even higher; hence the manifest danger of 35 cracking petroleum oil under such high pressures.

The present invention relates to a process of cracking petroleum and distillate in a still such as the still used in the Burton 40 process, but which eliminates the production of coke on the walls of the still, thereby obviating all danger due to the weakening of the steel at the points where the coke usually accumulates.

Another fact brought out in the "Burton process" is that the deposition of coke on vertical heating surfaces is very much less, being about one-third to one-fifth of the amount deposited on the upper side of a

horizontal surface, such as an ordinary still bottom, in a given length of time.

An object of my invention therefore is to provide a heating element for the cracking of petroleum and distillates in which the heating surfaces are practically all vertical, 60 thereby eliminating the deposition of coke to an appreciable extent.

Also, in the petroleum cracking industry, it has been shown that the ratio between the volume of oil heated and the area of the 65 heating surface of the apparatus employed is an important factor. This relation may perhaps be more clearly understood if it is stated that, other conditions remaining the same, cracking does not occur throughout 70 the mass of heated oil, but that the cracking effect produced in a given quantity in a given time will, within certain limits, be approximately proportional to the heated surface in contact with the oil. 75

Another important object of my invention is the provision of means whereby a thin film of oil is always maintained in contact with the heating element and the heating element itself is constructed so that 80 a maximum amount of heating surface is provided in a minimum amount of volume of the heating element.

A further object of my invention is the provision of means whereby part of the heat 85 generated for the cracking of the distillate is electrically produced, and this is accomplished by means of a high frequency, high voltage current which produces eddy currents of great amperage which generate the 90 heat in a heating element contained in the still itself.

A still further object of my invention is to provide a method of utilizing any excess heat which is generated by my process in 95 heating an additional quantity of oil for a succeeding process of fractional distillation or cracking in another still.

Another object of the invention is the use of a high voltage, high frequency current of small amperage which results in the production of an oscillating magnetic field through which the oil passes, and this produces a high molecular tension in the oil, 100 causing the molecules of the heavier hydrocarbons to break down or crack with greater ease and also tends to the practical elimination of the production of fixed gases. 105

Other and further important objects of this invention will be apparent from the disclosures in the drawings and specification.

The invention (in a preferred form) is 5 illustrated in the drawings and hereinafter more fully described.

On the drawings:

Figure 1 is a side elevation of an apparatus constructed in accordance with my in- 10 vention.

Figure 2 is an enlarged side view, partly in section, of a single still head showing my particular cracking cells installed therein.

Figure 3 is a sectional view of a cell taken 15 on the line 3-3 of Figure 2.

Figure 4 is a sectional view of the same cell taken on the line 4-4 of Figure 2.

Figure 5 is another sectional view of the cell taken on the line 5-5 of Figure 2 with 20 parts in elevation.

As shown on the drawings:

The apparatus consists essentially of a still 6 connected by suitable piping 8 to a condenser 10 and a receiver 12 for the condensed product, all connected in an air-tight manner and adapted to be operated under pressure. A gas vent 14 is provided in the receiver in order to permit the escape of accumulated gases if the pressure in the system should rise above a predetermined point.

The still 6 is suitably set in a foundation 16, made of brick or concrete, or any suitable material, to permit of the still being heated by a coal or gas fire in the usual way, a furnace therefor being provided at 18 and a flue at 19. The temperature in the still and vapor delivery pipe is maintained at about the end boiling point of gasoline which is a 30 variable factor dependent upon the pressure on the system. Located within the still and adjacent the bottom thereof are what I term the cracking cells or chambers, which constitute the chief elements of my invention, and one or more are installed in each still according to the capacity thereof. These cracking cells consist of an outer double-walled jacket 20 of metal having communicating therewith pipes 22 and 24, which extend out of the still proper and permit of circulating a fluid medium through said jacket for purposes of temperature regulation and also for heat exchange. This jacket is constructed with an external hood 26, the edge of which extends below a series of openings 28, communicating between the interior chamber enclosed by the double-walled jacket 20 and the interior of the still proper. This hood is designed to fill with the vapors of the low boiling point products as they are formed within the interior of the cracking cells 20 and the vapors prevent the flow of liquid oil through the cell by thermo-siphonic action. Oil enters the cell through the holes 30 near the

base of the cell, but liquid oil does not flow out through the holes 28. The oil which enters at 30 passes up between the wires 42 as explained below. This motion is due to thermo-siphonic action but before the oil 70 arrives at the top of the cell it has been cracked and the vapors resulting fill the hood 26 to the exclusion of liquid oil. The sides of the double-walled jacket are also provided with holes 30 near the base, which 75 permit the easy entrance of oil from the still to replace that which is cracked and escapes as a vapor through the upper holes and under the hood. The walls of these holes 30 may be inclined upwardly and inwardly to 80 prevent the backing up and escape there-through of the more highly heated oils within the cell.

Within the chamber enclosed by the double-walled jacket 20 is placed a coil of metallic tubing or suitably constructed stranded wire cable 32 consisting of a number of turns in the form of a helix, one end 34 of which is grounded to the chamber or to the still in a suitable manner to conduct electric 90 current, and the other end of this coil passes through an insulating bushing 36 of porcelain or other suitable material located in the sides or top of the jacket and thence is electrically connected by a cable 38 through 95 another insulating bushing 40 in the still or still head to the external electrical apparatus which forms an important part of this invention. Within the helical coil 32 contained in the cracking cell and supported by 100 an insulating base 33 of porcelain or the like is a bundle of loosely bound rods or metallic wires 42, whose length runs vertically through said coil or helix. The spaces between these rods or wires constitute the area, 105 in which the cracking effect is induced in the oil body, and by reason of the great heat generated, the large surface area presented, and the thinness of the sheets of oil, cracking is effected with great rapidity and 110 little fixed gases are produced because the temperature may be easily regulated and held very close to that necessary for proper cracking without the necessity of approaching that temperature at which decomposition 115 occurs, as is the case where the heat is applied externally and must be conducted through a large body of oil.

The external electrical apparatus consists of a spark gap 44, a condenser 46 and a voltage transformer 48 suitably connected to a source of alternating current through a manually operative variable reactance regulator or pair of choke coils 50 and 52, the whole designed and so proportioned as to produce a high frequency oscillating electric current through the condenser 46, spark gap 44, connecting leads 54 and 56 and the helix 32 enclosed by the double-walled jacket 20 of the cracking cell.

A blowout pipe for the cell is provided at 58, which communicates with the interior of the cracking cell and is adapted to allow the escape of the oil within the cracking 5 cell at desired intervals. Any free carbon liberated during the cracking process exists as a finely divided suspension and is practically confined within the cracking cell. The blowout pipe offers a means of removing 10 this at intervals without the necessity of checking the operation of the still, the free carbon mixed with the oil being ejected as a sludge. The distillates to be cracked into gasoline are fed into the still by a pipe, and 15 the level of the oil in the still is maintained at a constant value, this being determined by means of the gauge 62, the pressure being determined and regulated by gauge 84 and safety valve 86, while a thermometer is 20 provided at 88.

The operation is as follows:

Oil or distillate, preferably the latter, having been introduced into the still by means of the pipe 61, is heated therein by externally 25 applied heat in the furnace 18 until a temperature and pressure approximating that of the end point of gasoline at the given pressure is attained. Then the transformer 48 is brought into operation and comparatively 30 low voltage currents of great amperage are thereby induced in the bundle of rods or wires 42, these high amperage currents being called "eddy" or "Foucault" currents. The passage of the current of high frequency 35 through the helix 32 induces these "eddy" or "Foucault" currents in the bundle of wires 42, which are preferably made of iron or copper, but may be made of any suitable material, and metals acting as catalysts, 40 such as nickel, are especially advantageous with some classes of oils. These "eddy" currents result in the production of great heat, part of which heat is due to hysteresis. Further, the high frequency oscillating 45 magnetic field produced around the helix 32 passes through the thin films of oil surrounding the rods or wires of the core 42 and results in the production of a high molecular tension in the oil. This molecular tension, 50 together with a suitable heat and a proper pressure maintained on the system, causes the molecules of the heavier hydrocarbons to break down or crack with ease into low-boiling point hydrocarbons of the saturated class, and the production of fixed 55 gases is very low.

As the low boiling point products are formed, these being vapors at the temperature of the surrounding oil in the still 60 proper, escape under the edge of the hood, rise through the surrounding oil body and pass out through the delivery pipe 8 in the still head to the condenser 10, and thence as a liquid to the receiver 12. These products, 65 vaporized at the higher temperature within

the core of rods 42, which possess a boiling point above that of the desired product, are condensed by contact with the double-walled jacket through which is circulating a suitable medium at the correct temperature to 70 absorb this excess heat, and if any vapor escapes under the hood with the vapors of said product it becomes condensed within the oil in the still during its upward passage through the same. In either event, all of 75 the vaporized products with a boiling point above that of the desired end point for a given pressure are eventually returned to the cracking cell for further treatment.

I propose, in cases where it may be feasible, to pump crude oil through the double-walled jacket 20, as shown in Figure 1, by means of the pump 60 and pipe 22. This oil, after cooling the vapors in the cracking cell, will emerge through the outlet pipe 24 80 and will then be conducted to an ordinary straight run still 66, which still is provided with a pipe 68 leading to a condenser 70 and a receiver 72, likewise provided with a vent pipe 74. This crude oil, after being introduced into the still 66, will, with a slight addition of heat, be fractionally distilled and the gasoline and kerosene cuts made. Thus the excess heat of the cracking cell transferred to this oil by means of the 95 double-walled jacket can be made to serve a useful purpose in preparing the crude oil for further cracking treatment and in removing its originally contained gasoline and kerosene. The working pressure of the system may vary in practice from a few pounds 100 gauge to as much as 80 pounds gauge, dependent upon the origin and nature of the oils being treated and the characteristics of the product desired. The input of electrical 105 energy is conveniently regulated by the adjustment of the variable reactance regulators 50 and 52, and in practice electrical energy may be raised from the zero point until a maximum amount of gasoline is distilling 110 over associated with a minimum amount of fixed gases.

It will be seen that herein is provided a new and novel means for continuously cracking petroleum and distillates in which the 115 heat applied to the distillate is electrically generated and highly concentrated, thereby eliminating practically all of the troubles due to the accumulation of carbon in the still, and further taking advantage of the 120 high molecular tension due to the passage of the high frequency electric current which aids to break up the hydrocarbon molecules.

Also, by this apparatus the troubles and danger due to the deposition of hard flinty coke on the walls of the still are completely avoided and the fact that coke does not so readily accumulate on a vertical heating surface is taken advantage of in a highly efficient manner. Another beneficial result 125 130

is attained in the conservation of fuel by the heat exchange apparatus, in which the crude oil used in one still as a condensing medium is kept heated and by a further slight addition of heat is then fractionally distilled in a second still. Further economy of heat is effected, because in the operation of an ordinary cracking still, so much excess heat must be applied that a great many heat units are dissipated and lost, while in this process only a moderate heat is applied from the outside of the still, being that necessary to bring the contents to about 410° F. at atmospheric pressure, and the additional heat necessary to effect the cracking is developed directly in the cracking cell and is therefore highly concentrated with a minimum of loss.

I am aware that many details in the construction and operation of both the cracking and electrical apparatus may be varied through a wide range, and I therefore do not desire to limit the patent, when granted, otherwise than is necessitated by the prior art.

25 25 I claim as my invention:

1. In an apparatus for cracking oil by heat and pressure, a multitude of closely situated vertical metallic surfaces and means surrounding them for electrically heating the same.

2. In an apparatus for cracking oil comprising a gas-tight still, a condenser and a receiver, a heating element including a bundle of metallic rods within the still sur-

rounded by a helix adapted to carry high frequency electric current.

3. In an apparatus for cracking oil including a still and a furnace for heating the still externally, an electrically heated cracking cell in the still, a hood enclosing the upper portion of the cell, and means for automatically returning any vaporized products having a boiling point above that of the desired product to the cell for further treatment.

4. In an apparatus for cracking oil comprising a gas-tight still, a condenser and a receiver, a heating element including a bundle of metallic rods within the still, surrounded by a helix adapted to carry high frequency oscillating current, and a generator for such current including a condenser and a spark gap.

5. In an apparatus for treating oils including a still, a heating element in the still, said heating element being composed of a bundle of metallic rods surrounded by a helix adapted to carry high frequency oscillating current and enclosed in a jacket having openings at the top and bottom thereof, the openings at the bottom allowing the ingress of oil and the openings at the top permitting the escape of vapors, and a hood at the top of said jacket in which the vapors are allowed to collect.

In testimony whereof I have hereunto subscribed my name.

CARL M. PAGE.
